UNITED STATES PATENT OFFICE

2,610,534

SLIDABLE OUTER JAW PLIER-TYPE
WRENCH

Ernest H. Shaff, Spring Lake, Mich.

Application June 14, 1948, Serial No. 32,808

6 Claims. (Cl. 81—84)

1

This invention relates to improvements in slidable outer jaw plier-type wrench.

The main objects of this invention are:

First, to provide a wrench having a wide range of adjustment which is easily and quickly manipulated and at the same time has a very effective gripping engagement with the work.

Second, to provide a wrench of this type which may be formed of comparatively light stock and at the same time is strong and durable.

Third, to provide a wrench having these advantages which may be economically produced and is very convenient to operate.

Further objects relating to details and economies of the invention will appear from the description to follow. The invention is pointed out in the claims.

Preferred embodiments of the invention are illustrated in the accompanying drawings, in which:

Fig. 1 is a side elevational view of my wrench shown in closed position by full lines and in open position by dotted lines.

Fig. 2 is an under edge elevational view looking from the left of Figs. 1 and 3.

Fig. 3 is a fragmentary view mainly in longitudinal section, parts being shown in full lines for convenience in illustration.

Fig. 4 is a cross sectional view on a line corresponding to line 4—4 of Fig. 3, the adjusting nut being shown in full lines.

The embodiment of my invention illustrated comprises a tubular handle 1 of flattened cross section having a longitudinal slot 2 on its under side and opposed side openings 3. The outer jaw member 4 comprises a jaw 5 and shank 6 slidably fitting within the handle. This outer jaw member is provided with a threaded inner portion 7 engaged by the adjusting nut 8 which projects through the side openings 3 to facilitate adjustment of the nut. The nut sustains the end thrust on the jaw member.

The inner jaw 9, which in the embodiment illustrated is formed as a sheet metal stamping, is forked or bifurcated to provide arms 10 which embrace and are pivoted to the handle at 11. The actuating lever 12 is provided with an outwardly offset forward end 13, pivoted to the inner jaw 9 at 14. The toggle link 15 is pivoted within the handle at 16 and is pivotally connected to the actuating lever, which is of inwardly facing channel section, at 17. The pivot 17 is positioned so that the link 15 mainly collapses in the handle through the slot 2 thereof when the lever is in actuated position as is shown in Fig. 3.

2

The pivot 17 swings across a plane extending through the pivots 14 and 16 so that when the lever is in actuated position a locking toggle is provided for holding the jaw in its closed or actuated position. A coil spring 18 is arranged on the pivot 14 and is provided with a terminal arm 19 engaging the jaw and a terminal arm 20 engaging the actuating lever so that the spring tends to open the jaw when the toggle is broken.

10 The operating lever is of such cross section as to embrace the inner edge of the handle when in actuated position and to provide an effective grip element, that is, the handle and the lever are both grasped in the manipulation of the wrench after the jaw is closed.

To permit opening of the wrench with the hand grasping the wrench, I provide a release or trip lever 21 which is pivoted within the actuating lever 12 and extends forwardly therein and terminates in a laterally disposed finger piece 24 in the lever. This tripping lever fulcrums at 25 on the inner side of the handle so that pressure on the finger piece breaks the toggle, thereby opening the wrench by retracting the pivoted jaw.

25 This permits a one hand operation, that is, both hands are not required to open the jaws.

The shank 6 is preferably graduated as indicated at 26, the graduation being provided with indicia 27 which facilitates the adjustment of the wrench for a particular piece of work.

30 My improved wrench with the parts arranged as indicated and described is capable of very wide range of adjustment and of uses, is light, and conveniently operated. I have illustrated and described my invention in a highly practical embodiment thereof. I have not attempted to illustrate or describe various modifications or adaptations which I contemplate as it is believed that this disclosure will enable those skilled in the art to embody or adapt my invention as may be desired.

Having thus described my invention, what I claim as new and desire to secure by Letters Patent is:

45 1. In a wrench the combination of a tubular handle of flattened cross section having a longitudinal slot in its under side and opposed side openings, an outer jaw having a shank slidably within said handle and provided with a threaded portion at its inner end, an adjusting nut for said outer jaw threaded upon its said threaded portion and disposed to project into said opposed side openings to facilitate manipulation and support the outer jaw in its adjusted positions, an inner jaw forked to embrace said handle and pivotally

mounted thereon, an actuating lever of inwardly facing channel section having an offset at its outer end pivotally connected to said inner jaw adjacent its outer end, a toggle link pivoted at its rear end within said handle and pivoted at its forward end within said lever to collapse into said slot in said handle, the pivotal connection for the forward end of said link to said lever being adapted to swing across a plane extending through the pivotal connections for the lever to the inner jaw and for the link to the handle whereby a toggle lock is provided when the lever is in actuated position, a spring arranged on the pivot connecting said actuating lever and inner jaw and having terminal arms, one of which engages the jaw and the other the lever whereby the spring acts to urge the actuating lever and inner jaw to open position, and a toggle release lever pivotally mounted within said actuating lever to fulcrum on said handle and provided with a finger piece projecting through the under side of said actuating lever adjacent its forward end, said actuating lever being of such cross section as to embrace the under side of the handle when in actuated position and constituting a grip element when in actuated position.

2. In a wrench the combination of a tubular handle of flattened cross section having a longitudinal slot in its under side and opposed side openings, an outer jaw having a shank slideable within said handle and provided with a threaded portion at its inner end, an adjusting nut for said outer jaw threaded upon its said threaded portion and disposed to project into said opposed side openings to facilitate manipulation and support the outer jaw in its adjusted positions, an inner jaw forked to embrace said handle and pivotally mounted thereon, an actuating lever of inwardly facing channel section having an offset at its outer end pivotally connected to said inner jaw adjacent its outer end, a toggle link pivoted at its rear end within said handle and pivoted at its forward end within said lever to collapse into said slot in said handle, the pivotal connection for the forward end of said link to said lever being adapted to swing across a plane extending through the pivotal connections for the lever to the inner jaw and for the link to the handle whereby a toggle lock is provided when the lever is in actuated position, a spring arranged on the pivot connecting said actuating lever and inner jaw and having terminal arms, one of which engages the jaw and the other the lever whereby the spring acts to urge the actuating lever and inner jaw to open position, said actuating lever being of such cross section as to embrace the under side of the handle when in actuated position and constituting a grip element when in actuated position.

3. In a wrench the combination of a tubular handle of flattened cross section having a longitudinal slot in its under side and opposed side openings, an outer jaw having a shank slideable within said handle and provided with a threaded portion at its inner end, an adjusting nut for said outer jaw threaded upon its said threaded portion and disposed to project into said opposed side openings to facilitate manipulation and support the outer jaw in its adjusted positions, an inner jaw forked to embrace said handle and pivotally mounted thereon, an actuating lever of inwardly facing channel section having an offset at its outer end pivotally connected to said inner jaw adjacent its outer end, a toggle link pivoted at its rear end within said handle and pivoted at

its forward end within said lever to collapse into said slot in said handle, the pivotal connection for the forward end of said link to said lever being adapted to swing across a plane extending through the pivotal connections for the lever to the inner jaw and for the link to the handle whereby a toggle lock is provided when the lever is in actuated position, said actuating lever being of such cross section as to embrace the under side of the handle when in actuated position and constituting a grip element when in actuated position.

4. In a wrench the combination of a tubular handle of flattened cross section having a longitudinal slot in its under side and opposed side openings, an outer jaw having a shank slideable within said handle, an adjusting nut having threaded engagement with said shank and disposed to project into said opposed side openings to facilitate manipulation and support the outer jaw in its adjusted positions, an inner jaw pivotally mounted on said handle, an actuating lever of inwardly facing channel section having an offset at its outer end pivotally connected to said inner jaw adjacent its outer end, a toggle link pivoted at its rear end within said handle and pivoted at its forward end within said lever to collapse into said slot in said handle, the pivotal connection for the forward end of said link to said lever being adapted to swing across a plane extending through the pivotal connections for the lever to the inner jaw and for the link to the handle whereby a toggle lock is provided when the lever is in actuated position, a spring acting to urge the actuating lever and inner jaw to open position, and a toggle release lever pivotally mounted within said actuating lever to engage said handle and provided with a finger piece projecting through the under side of said actuating lever adjacent its inner end, said actuating lever being of such cross section as to embrace the under side of the handle when in actuated position and constituting a grip element when in actuated position.

5. In a wrench the combination of a tubular handle of flattened cross section having a longitudinal slot in its under side and opposed side openings, an outer jaw having a shank slideable within said handle, an adjusting nut having threaded engagement with said shank and disposed to project into said opposed side openings to facilitate manipulation and support the outer jaw in its adjusted positions, an inner jaw having a fixed pivotal connection to said handle, an actuating lever of inwardly facing channel section having an offset at its outer end pivotally connected to said inner jaw adjacent its outer end, and a toggle link having a fixed pivotal connection at its rear end within said handle directly to said handle and pivoted at its forward end within said lever to collapse into said slot in said handle, the pivotal connection for the forward end of said link to said lever being adapted to swing across a plane extending through the pivotal connections for the lever to the inner jaw and for the link to the handle whereby a toggle lock is provided when the lever is in actuated position.

6. In a wrench the combination of a handle, an outer jaw having a shank slideable within said handle, an adjusting nut for said outer jaw having threaded engagement therewith disposed to project from said handle to facilitate manipulation and to support the outer jaw in its adjusted positions, an inner jaw having a fixed pivotal

connection to said handle at its forward end, an actuating lever pivotally connected to said inner jaw at a point spaced from its connection to said handle, a toggle link having a fixed pivotal connection at its rear to said handle directly to said handle and pivoted at its forward end to said lever, the pivotal connection for the forward end of said link to said lever being adapted to swing across a plane extending through the pivotal connections for the lever to the inner jaw and for the link to the handle whereby a toggle lock is provided when the lever is in actuated position, and a toggle release lever pivotally mounted on said actuating lever to engage on said handle and provided with a finger piece projecting through the said actuating lever adjacent its forward end.
